W. DOUDEN

NOISE DEADENER FOR TYPEWRITING MACHINES

Filed March 12, 1923

Inventor

William Douden

By M. Saunders

Attorney

UNITED STATES PATENT OFFICE.

WILLIAM DOUDEN, OF WASHINGTON, DISTRICT OF COLUMBIA.

NOISE DEADENER FOR TYPEWRITING MACHINES.

Application filed March 12, 1923. Serial No. 624,679.

To all whom it may concern:

Be it known that I, WILLIAM DOUDEN, a citizen of the United States, residing at 1840 Biltmore St., in Washington, District 5 of Columbia, have invented certain new and useful Improvements in Noise Deadeners for Typewriting Machines, of which the following is a specification.

My invention relates to noise deadeners 10 for typewriting machines which may be readily introduced between the platen and the paper simultaneously with the paper.

One of the objects of my invention is the production of a device which may be employed in the ordinary typewriting machine 15 and which will appreciably reduce the noise of the operation thereof.

Another object of the invention is the provision of a noise deadener for a type- 20 writing machine which will also serve as a protection for the platen thereof.

Another object of the invention is the production of a device which will improve the impressions of the carbon copies and 25 which will at the same time assist in holding the several sheets of paper and carbons together while they are being fed into and through the machine.

A further object of the invention is the 30 production of a device which will soften the touch of the keys to the finger tips.

I attain the above and other objects of the invention by means of the device illustrated in the accompanying drawing, being a perspective view of the device, in which:

A represents a moderately hard, resilient, pliable material such as celluloid; B represents a sheet of chamois skin, felt, soft rubber or similar cushioning material which is 40 made closely adherent to the sheet of celluloid by means of a suitable adhesive.

The celluloid sheet has a portion of its top edge turned down, as shown at C, in order to receive the sheets of paper and to 45 hold them in position while they are being fed through the machine. As many as six sheets of paper and five carbons may be used with this device and can be removed from and fed again into the typewriting machine 50 without any change in the alignment of the sheets. As an obvious modification, tongues might be cut out from the sheet of celluloid

and bent away from the main sheet in order to provide clips for the same purpose as the turned over edge C. 55

In the use of the article, the soft backing not only serves as a protection for the roller, deadens the sound of the keys, but also, because of the cushioning action it provides for the character carriers, protects the finger tips of the operator. The relatively smooth, hard surface of the celluloid sheet against which the paper rests materially aids in making a clear impression, while the cushioning material deadens the sound of the keys striking against the device. It is also within the scope of my invention to roughen the surface of the celluloid slightly in order to prevent slippage of the paper which rests against it. 65 70

While the use of chamois skin and celluloid is preferable, it is obvious that other materials might be employed as substitutes therefor, for instance, felt, rubber or cloth might be used in place of chamois skin, while hard rubber might be substituted for the celluloid. Another desirable substance to be used in place of the celluloid is material such as employed as a backing for photographic films, especially that known 80 by the trade name of "kodaloid". 75

If a transparent material such as celluloid is employed, the under side of the sheet might be printed with data, rules, tables or an advertisement, thus making the device 85 serve several useful purposes.

Having fully described my invention, what I claim and desire to secure by Letters Patent is:—

1. A noise deadener for typewriting machines adapted to be inserted into the machine simultaneously with the paper comprising a sheet of flexible, smooth surfaced material and a sheet of cushioning material closely adherent to said first named sheet. 90 95

2. A noise deadener for typewriting machines comprising a sheet of flexible material and a sheet of cushioning material adhering thereto, said first named sheet being provided with paper retaining means. 100

3. As an article of manufacture, a sheet of relatively hard, flexible material and a sheet of cushioning material, said sheets being fastened together, the combined thick-

ness of which being such as to permit their easy insertion into the typewriting machine between the platen and the paper simultaneously with the paper.

5. 4. A noise deadener for typewriting machines adapted to be readily introduced into the machine between the paper and the

platen simultaneously with the paper, comprising a composite sheet of material the upper surface of which is relatively hard, ¹⁰ the remaining portion of the sheet being of cushioning material.

In testimony whereof I affix my signature.

WILLIAM DOUDEN.
